US0D1097130S

(12) **United States Design Patent** (10) **Patent No.:** **US D1,097,130 S**
(45) **Date of Patent:** **** Oct. 7, 2025**

(54) **MEDICAL INJECTOR**

(71) Applicant: **Sensile Medical AG**, Olten (CH)

(72) Inventor: **Milan Kolenda**, Trimbach (CH)

(73) Assignee: **Sensile Medical AG**, Olten (CH)

(**) Term: **15 Years**

(21) Appl. No.: **29/940,341**

(22) Filed: **May 1, 2024**

Related U.S. Application Data

(62) Division of application No. 35/516,104, filed on Nov. 4, 2022 (U.S. filing date under 35 U.S.C. 384), and having an international filing date of Nov. 4, 2022, now Pat. No. Des. 1,026,217.

(57) **CLAIM**

The ornamental design for a medical injector, as shown and described.

DESCRIPTION

FIG. 1 is a perspective view of a medical injector showing my new design;

FIG. 2 is a front view of the medical injector;

FIG. 3 is a rear view of the medical injector;

FIG. 4 is a right side view of the medical injector;

FIG. 5 is a left side view of the medical injector;

FIG. 6 is a top view of the medical injector; and,

FIG. 7 is a bottom view of the medical injector.

The broken lines showing in the Figures are included for the purpose of illustrating portions of the medical injector that form no part of the claimed design.

1 Claim, 7 Drawing Sheets
